UNITED STATES PATENT OFFICE.

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK.

LIGHT-REACTIVE APPARATUS.

Application filed January 11, 1923. Serial No. 611,979.

This invention relates to a certain new and improved light reactive apparatus.

The object of the invention is the production of an apparatus of the character described which may be produced at less cost and may be operated at less expense than similarly used apparatus as constructed at the present time without in any way decreasing the efficiency of the apparatus. More specifically the use of peculiar circuits permits the elimination of one of the sources of potential commonly used in such hookups.

In the drawings there is illustrated an apparatus of my invention.

15 The apparatus comprises an electron discharge device including the usual bulb —1— enclosing a filament —2—, a grid —3— and a plate —4—.

The filament may be heated in any manner, as by the usual heating circuit, including a source of potential —5—. The filament —2— is connected in circuit with the plate —4—, such circuit including a source of potential —9— and a translating device 25 such as telephonic receivers —10—. The light reactive cell —6— is connected in a circuit including the conductor —7— leading to the grid —3— and the conductor —8— tapped into the plate filament circuit 30 between the source of potential —9— and the plate —4—.

By this arrangement of divided circuits, I am able to produce an apparatus utilizing a single source of potential that is equally as effective as the usual and known apparatus 35 in which a separate source of potential, such as a battery, is interposed in the circuit which directly includes the light reactive cell as well as a separate source of potential in 40 the circuit, including the translating device —10—.

It will be apparent that with the present hook-up the current may flow from battery —9— to the plate —4—, then across to the 45 filament —2— and back to the battery, and at the same time current may flow from bat-

tery —9— thru the conductor —8— to the light reactive cell and through conductor —7— to the grid —3—, then from the grid to the filament and back to the battery —9—. 50

By this arrangement of circuits, I am able to accomplish a highly efficient result with the utilization of a single battery, which battery is common to both the primary light reactive circuit and the translating circuit. 55

Amplification may be continued thru the usual steps or stages by substituting the primary of a transformer for the translating devices —10— and connecting the usual circuits from there on with the secondary of 60 such transformer, all in the usual and well known manner.

Altho I have shown and described a specific structure as illustrative of my invention, I do not desire to restrict myself to 65 the details of the structure, as various changes may be made without departing from the invention as set forth in the appended claims.

I claim:

1. A light reactive apparatus comprising a three electrode electron discharge device, a circuit connecting the filament and plate of said device, a circuit connecting the filament and grid of said device and containing a 75 light reactive resistance, and a single source of potential common to both of said circuits and adapted to energize both of said circuits.

2. A light reactive apparatus comprising an electron-discharge device including a filament, a grid and a plate, a circuit connecting the filament and plate of said device and containing a source of potential, a light reactive resistance, a conductor connecting the light reactive resistance to the grid of said device, and a conductor connected to the light reactive resistance and tapped into the filament plate circuit intermediate the said source of potential and the plate. 80

In witness whereof I have hereunto set my hand this 6th day of January 1923.

THEODORE WILLARD CASE.
